UNITED STATES PATENT OFFICE.

ALBERT BANDMAN, OF NEW YORK, N. Y.

SYRINGE.

Application filed March 19, 1921. Serial No. 453,563.

To all whom it may concern:

Be it known that I, ALBERT BANDMAN, a citizen of the United States, residing at New York, in the county of New York and State 5 of New York, have invented certain new and useful Improvements in Syringes; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to syringes, and particularly to hypodermic syringes. It has for its object to provide improved features of construction and combination of parts which will afford a practically complete, effective seal at both ends of the plunger barrel so that the possibility of any leakage is prevented, and under which the several parts comprising the barrel, the casing or shell, and the caps at opposite ends may be 20 readily assembled and disassembled as occasion demands without impairing the efficiency of the seal.

To the accomplishment of the foregoing and such other objects as may hereinafter 30 appear the invention consists in the features hereinafter particularly described and then sought to be clearly defined by the claims, reference being had to the accompanying drawing forming a part hereof, and in 35 which—

Figure 1 is a side elevation of the syringe with all parts assembled;

Figure 2 is a vertical section through the 40 syringe, taken at right angles to Figure 1;

Figure 3 is a perspective of the shell or casing and inner glass barrel, with other parts omitted;

Figure 4 is a vertical section through the 45 lower cap of the syringe.

In the drawing the numeral 1 designates the inner glass barrel which receives the medicament or liquid for injection and in which is fitted to reciprocate therein the plunger 2 whose outside diameter corresponds to the inside diameter of the glass 50 barrel, the plunger being provided at its upper end with the angular extending hand or thumb rest 3 for movement of the plunger. The glass barrel is encased or enclosed 55 in a metal shell or casing 4 which has a length slightly less than that of the glass

barrel so that both ends of the barrel may extend beyond the ends of the shell to serve a purpose hereinafter stated. The shell has portions of its wall removed to form 60 an opening or openings 5 through which may be observed the contents of the glass barrel, which latter may be inscribed with a scale 6 to serve as an indicator for the measured dose of medicament to be administered, and both ends of the shell are provided externally with threads 7 for the attachment of end caps formed as hereinafter described for securing the shell and barrel together and also for confining and placing 65 under compression washers for effecting a non-leaking connection or seal between the glass barrel and securing caps. Each cap is formed in a special manner to more efficiently discharge the function for which 70 specially designed. The lower cap is designated by the numeral 8 and is cup-shaped and formed internally with screw threads 9 to engage the external threads of the shell 4 and with a centrally disposed hollow nipple 10 extending upwardly from the bottom of the cap, adapted to fit within the end of the glass barrel, and encircled by an annular 75 rib or ridge 11 extending up from the bottom of the cap and disposed to be in alinement with the end of the glass barrel, and is formed externally with a threaded apertured nipple 12 projecting from the bottom of the cup and adapted to have screwed thereon the hub 13 of the hypodermic needle 80 85 90 14. The upwardly extending nipple 10 serves to center the glass barrel and to hold in place beneath the projecting end of the glass barrel any desired number of washers 15, which in the present and preferred instance are felt washers, chemically prepared to sterilize and render the same liquid proof or resisting. When the cap 8 is screwed 95 into position these washers are compressed as shown in Fig. 2, between the projecting end of the glass tube and the rib 11 which projects from the bottom of the cap and is in alinement with the projecting end of the glass tube, and are confined by the walls 100 of the cap and the upwardly projecting nipple 10 so that a practically tight, non-leakable joint of sterilized liquid proof felt is formed at the lower end of the syringe. The upper end of the glass barrel and metal shell are closed by a cup-shaped cap 16 having 105 interior threads 17 to screw on to the metal shell and formed with an upwardly 110

extending threaded stem 18 through which the plunger 2 passes and also formed on its interior with an annular rib or ridge 19 disposed in alinement with the projecting end 5 of the glass barrel so that any desired number of washers 15, preferably chemically treated to render them liquid proof and sterilized, as at the other end of the syringe, will be compressed by the projecting end of 10 the glass barrel and the internal annular rib 19, when the cap is screwed into place, and thus form an effective tight seal at the joint between the cap, glass barrel and metal shell. The metal cap 16 is provided with a 15 finger-grip 20, preferably formed integral therewith, and onto its threaded stem 18 there is screwed a stuffing-box cap 21 formed on the interior of its top with an annular rib or ridge 22 disposed in alinement with 20 an upwardly extending rib 23 on the end of stem 18 so that a desired number of washers 24, preferably felt washers like the others mentioned, will be compressed and held tightly in place between the walls of the cap 25 and the plunger 2 and thus form a tight, liquid proof stuffing box for the plunger of the syringe.

The hub 13 of the needle 14 is formed with an annular rib or ridge 25 which will 30 imbed itself in and compress a metal washer 26 around the nipple 12 of cap 8 when the needle hub is screwed into place.

In assembling the parts, the plunger or piston 2 is inserted through the cap 16 with 35 its end projecting about an inch below the edge of the cap; the washers are then slipped over the piston and pressed into the cap; the metal shell is then screwed into the cap; the glass barrel is then slipped over 40 the plunger or piston; the lower cap 8 with the felt washers placed therein around its nipple 10 is then placed in position, with its nipple entering the glass barrel, and then screwed onto the threaded end of the metal shell, with the result that the felt washers 45 at the opposite ends of the glass barrel are compressed between the protruding ends of the barrel and the inwardly extending ribs or ridges of the upper and lower caps so 50 that opposite ends of the barrel and the ribs of the upper and lower caps are embedded in the felt washers and the edges of the washers are forced against the walls of the caps and against the plunger or piston 55 at the upper cap and the upwardly extending nipple of the lower cap so that a tight, liquid proof joint is formed at the lower and the upper ends of the glass barrel.

One important feature of the invention is 60 in the opposite ends of the medicament barrel protruding or projecting beyond the opposite ends of the encasing shell so that with the washers applied at opposite ends of the barrel and contained within the closure caps 65 they will be compressed between the ends

of the barrel and the caps on screwing the caps into place and thus produce a tight joint at both ends of the barrel. Another important feature is in providing each closure cap with an internal annular rib or 70 ridge in alinement with the end of the barrel so that as the washers are compressed the ends of the barrel and the internal ribs of the caps will embed in the washers thus firmly holding the washers in place under 75 a state of compression.

Another important feature is the provision of sterilized substantially liquid-proof 80 felt washers between the ends of the medicament barrel and the closure caps at opposite ends of the barrel so that the ends of the barrel will become embedded in felt under compression in order to make a tight substantially liquid-proof joint at such points. Another important feature is the 85 relative positioning of the medicament barrel, encasing shell, caps and washers which permits the easy assembling and disassembling of the parts without displacement of the washers from position to effect 90 a tight joint when assembled.

Having described my invention and set forth its merits what I claim is:

1. In a syringe, an outer shell, an inner medicament barrel having its opposite ends 95 protruding beyond the ends of the shell, closure caps applied to opposite ends of the shell, substantially leak-proof soft washers contained within the caps and having the ends of the barrel imbedded therein with the washers under compression to distend the washers laterally, and a piston within the barrel.

2. In a syringe, an outer shell, an inner medicament barrel having its opposite ends protruding beyond the ends of the shell, closure caps applied to opposite ends of the shell and each provided with an internal annular rib in alinement with the end of the barrel, washers contained within the caps and interposed between the ends of the barrel and the annular rib of the respective caps and having the ends of the barrel and the ribs imbedded therein with the washers under compression, and a piston within the 110 barrel.

3. In a syringe, an outer shell, an inner medicament barrel having its opposite ends protruding beyond the ends of the shell, closure caps applied to opposite ends of the shell, sterilized substantially liquid proof felt washers contained within the caps and having the ends of the barrel imbedded therein with the washers under compression to distend the washers laterally, and a piston within the barrel.

4. In a syringe, an outer shell, an inner medicament barrel, a closure cap applied to the injector needle end of the shell, said cap having an inwardly extending nipple enter- 130

ing the barrel and an inner annular rib between the nipple and wall of the cap, and washers within the cap and having the end of the barrel imbedded therein, with the washers under compression, and a piston within the barrel.

5. In a syringe, an outer shell, an inner medicament barrel, a closure cap applied to one end of the shell, said cap having an inner annular rib in alinement with the end of the barrel and an external upwardly extending threaded stem, a stuffing-box cap applied to said stem, washers interposed be-

tween said cap and the end of the stem, and washers interposed between the end of the barrel and inner annular rib of the closure cap, said washers being under compression between said rib and the end of the barrel and having the same imbedded therein, and a piston within the barrel.

10 In testimony whereof I affix my signature in presence of two witnesses.

ALBERT BANDMAN.
